UNITED STATES PATENT OFFICE.

FRANCIS T. JOHNSON, OF CHICAGO, ILLINOIS.

CLOTHES-DRYER.

1,128,318.

Specification of Letters Patent. Patented Feb. 16, 1915.

Application filed April 18, 1914. Serial No. 832,675.

To all whom it may concern:

Be it known that I, FRANCIS T. JOHNSON, a citizen of the United States, residing at Chicago, in the county of Cook and State 5 of Illinois, have invented a certain new and useful Improvement in Clothes-Driers, of which the following is a specification.

My invention relates to improvements in clothes driers and is illustrated diagrammatically in one form in the accompanying 10 drawings, wherein—

Figure 1 is a front elevation; Fig. 2 is a side elevation with parts broken away; Fig. 3 is a section along line 3—3 of Fig. 1; 15 Fig. 4 is a section along line 4—4 of Fig. 3; Fig. 5 is a section along line 5—5 of Fig. 2; Fig. 6 is a detail fragmentary section through the front end of a modified form of drier showing a hinged door; Fig. 20 7 is a detail of a modified form; and Fig. 8 is a detail of a modified form.

Like parts are indicated by like letters throughout the several figures.

A is a clothes drying chamber or casing 25 having side walls A¹, A¹ and a rear end wall A² and a front wall A³, the front walls being apertured as at A⁴.

B, B are what I have called stoves rectangular in cross section and closed at the 30 bottom by the baffle plates B¹ upwardly and rearwardly inclined, bounded on the front end by the wall A³ and closed at the rear end short of the wall A². These stoves contain burner pipes B² fed by gas 35 from any suitable source of supply B³ controlled by any suitable means not indicated. These stoves are supported from the walls A¹ by brackets B⁴. Mounted above these stoves and supported in position by the 40 brackets B⁵ are what I have called radiators B⁶ in communication with the stoves by means of the pipes B⁷. These radiators are comparatively large hot air chambers and are fed with heated air from the stoves 45 B. Pipes B⁸ project downwardly into the radiators B⁶ and communicate with the interior thereof at a point adjacent the bottom. These pipes pass upwardly through the top of the radiators and discharge into

50 one or more exhaust bays C grouped along the sides of the chamber A and supported from the walls A¹. These exhaust bays communicate with the interior of the chamber A at points adjacent the bottom. They 55 are closed at all sides and at the top and discharge through the piping C¹ into the

exhaust breeches C² at the top of the chamber which in turn communicates with the chimney or flue by means of the pipe C³. It will be noted that the radiators communicate only with the center bay of each group of three through the pipe B⁸. 60

D is an intake bay communicating by means of the apertures D¹ in the end wall of the casing with the outside air and discharging into the casing at a point adjacent its bottom. 65

D² are intake bays communicating through the holes D³ in the front wall of the casing with the outside air and discharging into the interior of the casing 70 at a point adjacent its top.

D⁴, D⁴ are dampers communicating with the stoves B adapted to be controlled by the adjustable shutter D⁵ to control the amount 75 of fresh air fed directly to the stove.

D⁶, D⁶ are ventilation apertures in the top of the walls A¹ protected by the downwardly depending hoods D⁷.

E, E¹ are tracks to guide one or more 80 racks which may be rolled into or out of the chamber A. In Fig. 4 I have shown two racks closed as at E², E³ at the front and rear so that the door or opening A⁴ is closed by these racks when either one is 85 in the fully opened or fully closed position.

E⁴, E⁴ are screens interposed between the racks and stoves B and radiators B⁶ to prevent contact of the clothes to be dried with the stoves or radiators and the resultant 90 burning.

In the modified form shown in Fig. 6, a door F is substituted for the ends of the racks E⁶ which door is adapted to be closed by means of a latch F¹. F² is an adjustable 95 bottom flap adjustably mounted on the door in order to permit adjustment of the door to close it completely when the floor upon which the drier rests is not exactly level. I propose to use ordinary trucks which may 100 be rolled into or rolled out of the drying chamber.

The use and operation of my invention are as follows: The fire is first lighted in the stoves, the gas being turned on and 105 lighted as it issues from the burner pipes in the usual manner. The air in the stove will, of course, be heated and this heated air, being lighter than the cold air outside, will pass up through the connection provided 110 into the radiator which will soon be filled with hot air. This hot air, of course, will

be replaced by cooler air from the interior of the heater, which cooler air is deflected upwardly and inwardly by the deflector vanes into the stoves and toward the dis-
 5 charges. The air will be free to circulate in the radiator and be drawn from the bottom thereof through the exhaust pipe into one of the exhaust bays whence it will pass up to the exhaust breeches and thence to
 10 the flue. A current of air will thus be induced and to this air will be added air drawn from the bottom of the heater passing up through all of the exhaust bays into the breeches and thence to the radiator.
 15 This air will be replaced by air entering the radiator at the top through the hooded apertures, by air entering it at the bottom through the intake bay D and by air entering through the damper into the stove.
 20 By this arrangement most of the cool air will enter at the top and be drawn down gradually heated to the bottom whence it will be discharged.

I claim:

25 1. A drier for clothing and the like comprising a housing, a burner chamber located adjacent the bottom of the housing, said burner chamber being open along its lower side, a heat drum located above the
 30 burner chamber and communicating therewith, combined heating and exhaust chambers located along the wall of the housing, a communication from them to the bottom of the heat drum and a discharge therefrom
 35 to the outer atmosphere.

2. A drier for clothing and the like comprising a housing apertured for air intake purposes adjacent its top, a heating chamber at the bottom of the housing and open
 40 toward its bottom, hot air chambers contained within said housing communicating respectively with the heating chamber and the outer atmosphere.

3. A clothes drier comprising a housing, a plurality of heating chambers located within the housing open at their bottoms and communicating with the housing, an exhaust manifold at the top of the housing, communications therebetween and the top
 45 of the chambers.

4. A clothes drier comprising a housing, a plurality of heating chambers located within the housing open at their bottoms and communicating with the housing, an
 55 exhaust manifold at the top of the housing, communications therebetween and the tops of the chambers, heating chambers and a heat chamber heated thereby and communications therefrom to said first mentioned
 60 heating chambers.

5. A drier for clothes and the like comprising a housing apertured at its top, a burner chamber at the bottom thereof, a burner therein, the bottom of the burner
 65 chamber being open to the interior of the

housing, a heat drum separated from the walls of the housing and located therein, a hot air communication from the burner chamber to the heat drum, heating chambers formed along the walls of the housing
 70 open at their bottoms and communicating at that point with the housing, an exhaust manifold, communications from the tops of said heating chambers to the exhaust manifold, and a communication from the bottom of the heating drum to one of said exhaust manifolds, and an exhaust pipe leading from the exhaust manifold out of the chamber.

6. A drier for clothing and the like comprising a housing apertured for air intake purposes adjacent its top, a heating chamber at the bottom of and contained within the housing and downwardly apertured in communication with the interior of the
 80 housing, a heating member located within said heating drum, and hot air chambers located within the housing in communication respectively with the heating chamber and with the outer atmosphere.
 90

7. A drier for clothes and the like comprising a housing apertured at its top, a burner chamber at the bottom thereof, a burner therein, the bottom of the burner chamber being open to the interior of the
 95 housing, a heat drum separated from the walls of the housing and located therein, and a hot air communication from the burner chamber to the heat drum.

8. A drier for clothes and the like comprising a housing apertured at its top, a burner chamber at the bottom thereof, a burner therein, the bottom of the burner chamber being open to the interior of the
 100 housing, a heat drum separated from the walls of the housing and located therein, a hot air communication from the burner chamber to the heat drum, and heating chambers formed along the walls of the
 105 housing open at their bottoms and communicating at that point with the housing.
 110

9. A drier for clothes and the like comprising a housing apertured at its top, a burner chamber at the bottom thereof, a burner therein, the bottom of the burner
 115 chamber being open to the interior of the housing, a heat drum separated from the walls of the housing and located therein, a hot air communication from the burner chamber to the heat drum, heating chambers formed along the walls of the housing open at their bottoms and communicating at that point with the housing, an exhaust manifold, and communications from the tops of said heating chambers to the ex-
 120 haust manifold.
 125

10. A drier for clothes and the like comprising a housing apertured at its top, a burner chamber at the bottom thereof, a burner therein, the bottom of the burner
 130

chamber being open to the interior of the housing, a heat drum separated from the walls of the housing and located therein, a hot air communication from the burner 5 chamber to the heat drum, heating chambers formed along the walls of the housing open at their bottoms and communicating at that point with the housing, an exhaust manifold, communications from the tops of 10 said heating chambers to the exhaust mani-

fold, and a communication from the bottom of the heating drum to one of said exhaust manifolds.

In testimony whereof, I affix my signature in the presence of two witnesses this 15 15th day of April 1914.

FRANCIS T. JOHNSON.
